UNITED STATES PATENT OFFICE

161,832

WOOD SAWING MACHINE

George M. Gustin, Wabash, Ind.

Application January 5, 1949, Serial No. 63

Term of patent 14 years

(Cl. D93—3)

To all whom it may concern:

Be it known that I, George M. Gustin, a citizen of the United States, residing at Wabash, State of Indiana, have invented a new, original, and ornamental Design for a Wood Sawing Machine, of which the following is a specification, reference being had to the accompanying drawing, forming a part hereof.

Fig. 1 is a front perspective view of a wood sawing machine, showing my new design; Fig. 2 is a side perspective view taken from the left of Fig. 1; and Fig. 3 is a perspective view taken from the right side and rear of Fig. 1.

I claim:

The ornamental design for a wood sawing machine, as shown.

GEORGE M. GUSTIN.
